UNITED STATES PATENT OFFICE

KARL A. MAYR, OF NEW YORK, N. Y., ASSIGNOR TO SIEMENS-SCHUCKERTWERKE AKTIENGESELLSCHAFT, OF SIEMENSSTADT, NEAR BERLIN, GERMANY, A CORPORATION OF GERMANY

STEAM GENERATOR

Application filed October 4, 1927. Serial No. 223,856.

This invention relates to improvements in steam generators and more particularly to improvements in steam generators of the flash type.

5 One object of the present invention resides in the provision of a construction which will provide for high and maximum output in a minimum space at maximum efficiency.

Another object is to provide a construction 10 in which heat losses by radiation, are reduced to a minimum by providing a construction having a minimum outside heat dissipating surface.

Another object resides in the provision of 15 a combustion chamber which is best adapted for proper combustion.

Another object resides in a novel arrangement of heat absorbing elements to the general and that radiant heat and heat from the 20 hot gases is more effectively absorbed than heretofore.

A further object resides in the provision 25 of a construction which obviates dead corners so that all hot flowing gases are effective in giving up heat and all parts of the apparatus act efficiently in absorbing heat.

A further object of the present invention resides in the provision of a construction which will be simple to assemble and dismantle 30 and which provides for free and independent expansion of the parts when in use.

A further object resides in the provision of 35 a novel preheater for incoming air which is concentric with the heat absorbing structure and combustion chamber whereby compactness is secured and whereby an air jacket is provided for the highly heated parts.

Further objects and advantages will be hereinafter set forth in the accompanying 40 specification and claims and shown in the drawings, which shows by way of illustration what I now consider to be one and a perfect embodiment of my invention.

In the drawings Figure 1 represents a 45 central vertical sectional view of the steam generator.

Fig. 2 is a cross-sectional view taken substantially on line 2—2 of Fig. 1.

Fig. 3 is a section taken on line 3—3 of 50 Fig. 1.

In more detail, the steam generator is suitably supported upon a base support 20. 21 designates a substantially cylindrical combustion chamber. This combustion chamber is slightly conical for improving combustion action and for facilitating disassembling of the various parts. The upper head of this combustion chamber generally designated 22, forms the subject matter of a separate application, Serial No. 223,857, filed October 4, 1927, and this part of the apparatus is adapted to suitably mix finely divided fuel and the air for combustion and to direct the burning mass downwardly into chamber 21 with a turbulent and whirling motion.

The various heat absorbing elements will now be described. 22 is a spiral tubular coil suitably supported on the base 20 and having its lower portion formed of loops generally designated 23, to provide open passages 70 from the combustion chamber in an outer direction as indicated by the arrows 24.

The incoming feed water is supplied through an inlet pipe such as 25. Just outside coil 22 is a tapered cylindrical shell 26

75 which secures its support by the frictional engagement of the coil 22 which is within it. It may be also suitably supported by spot welding if this is desired. The water entering coil 22 receives the intense radiant heat in

80 the combustion chamber 21 and is heated thereby and the coil 22 is further heated by the hot gases which sweep over its surface.

From coil 22 an outlet pipe 27 leads outwardly and downwardly and connects to a mud collector or trap 28. From the outlet 85 of this mud collector 28 a pipe 29 leads to a spiral coil 30 which is disposed in back of the lower portion of shell 26 to aid in protecting

said shell against the effects of the still highly heated gases. From the top of this 90 coil 30 a connection 31 leads to the inner of a number of coils 32. These coils are concentrically disposed one outside the other and the inner coil comprises a spirally disposed

95 tubular conduit which at the top as indicated by the arrow 34, connects to the next outer concentric coil 32. This is likewise a spiral

and from this coil the water or steam, as the case may be, is led to the next outer coil 32

at the bottom and through that coil to the next and outermost coil at the top as indicated by arrows 35 and 36. From the bottom of the outermost coil 32 a pipe 37 leads 5 to the throttling or reducing valve generally designated 38 and from this valve a further pipe 39 leads to the bottom inner coil of a tube nest generally designated 40. The circulation through this tube nest is generally 10 the same as for the nest 32, viz, up on the inside, then down, then up, then down and then up in the outer coil 40. From the top of the outer coil 40 a pipe 41 leads downwardly 15 completely out of the apparatus and eventually extends to the high pressure steam consumer generally designated 42. From this consumer the steam flows into a suitable intermediate receiver 43 and thence it returns 20 through a pipe 44 to the outer of a nest of spiral concentric coils 45. This nest constitutes a reheat for the steam. The steam after passing them flows again out of the apparatus through pipe 46 to the low pressure consumer.

25 It will be understood that the reheat 45 can be dispensed with if desired and when such reheat is dispensed with the coil nests 32 and 40 can be arranged with a lesser number of concentric convolutions and can occupy 30 the space previously occupied by the reheat. In this case the annular diameter could be somewhat decreased.

Outside the tube nests 40, 32 and 45, preheater boxes are provided. The inner walls 35 of these preheater boxes define the outer wall of the heat absorbing chamber for the tube nests 40, 32 and 45. These preheater boxes are best shown in Fig. 2 and comprise an inner curved wall portion 50 and an outer 40 wall portion 51 and connecting plate portions 52 suitably flanged and fastened to shell plates 50 and 51. To connect adjacent heater boxes together and to rigidly fasten the same to the base casting 20, each heater 45 box may be provided with an outer flange portion 53 suitably fastened thereto and between adjacent flanges 53, a plate 54 is provided which extends down into cooperation with the base 20. Suitable connecting bolts 50 afford means for connecting adjacent boxes to each other and to the plate 54.

The preheater boxes have disposed within them vertically extending pipes 56 which at their lower and upper ends are supported 55 by header plates 57 and 58 respectively. The tube spacing of the tubes 56 is such that the flow of air which is to be preheated is substantially equalized at inner, outer and intermediate points in the preheater chambers. 60 This may be effected by disposing the outer tubes with the same center to center spacing which is provided for those tubes which are relatively closer to the inner wall of the preheater as shown in the drawings, Figs. 2 and 65 3. In other words, the disposition of the

concentric tubes on radial lines should be avoided, which disposition, if adopted, would provide greater spacing for the outer rows of tubes than for the inner rows.

Without the preheater there is a casing 70 60 which is provided with suitable inlet ports 61 for the incoming air which is to be preheated. This air passes downwardly in chamber 62 and absorbs heat thereby cooling 75 the outer walls of the preheater.

From passage 62 the air passes into the preheaters as indicated by arrow 63 and flows upwardly around the preheater tubes. Suitable baffles 65 may be provided in the preheater boxes to avoid the formation of 80 dead corners, to increase the turbulence of the air, and to increase the velocity of air in order to improve the heat transfer conditions. Arrow 66 indicates the flow of the air as it leaves the preheater. The preheated air 85 goes into an annular chamber 67 and thence to an air chamber 68 from which it is admitted into the combustion chamber in the manner described in my copending application.

90 It will be understood that the hot gases from the combustion chamber traverse first the tube nest 40 thence tube nests 32 and 45 and afterwards pass into a header 69 disposed above the upper tube plate 58. From this header 69 the hot gases pass downwardly 95 within the tubes 56 and eventually pass out of the apparatus at a duct 70, which may be connected with any suitable exhaust fan.

It is contemplated that the particular 100 steam generator herein described is to operate with oil fuel, although it is suitable for other fuels. When oil fuel is utilized, there are times when oil may collect in the bottom of the apparatus. To provide for draining out such oil and to prevent coke from choking the outlet pipe for such oil, I provide a 105 tapered bottom refractory plate 71 having a central opening 72 closed by a manhole 73. This manhole is provided with an oil drain tube 74 having a flap valve 75 on its end 110 which opens automatically if the oil level rises in tube 74. To prevent clogging by coke I preferably provide a mushroom shaped cover 76 which cover has a series of oil drain grooves 77 in the bottom thereof 115 which lead to the open end of pipe 74.

What I claim is:

1. A steam generator comprising in combination a combustion chamber of tapered cylindrical contour which inwardly tapers 120 towards the bottom thereof, and heat absorbing tubes of corresponding contour, other heat absorbing tubes without said first mentioned tubes, said contour of the combustion chamber and of the first mentioned tubes facilitating assembly and disassembly of the tubes by permitting upward withdrawal of the first mentioned tubes with the other tubes in position.

2. A steam generator comprising in com- 125

- bination with a base, a combustion chamber, of heat absorbing means therein comprising a tube section disposed at and forming the wall of the combustion chamber, and a plurality of openly spaced loops connected to said tube section, said loops supporting the aforesaid tube section from the aforesaid base.
3. A steam generator comprising in combination with a combustion chamber, of a shell therearound and heat absorbing tubes frictionally engaging the shell and disposed to receive direct radiant heat from the combustion chamber, means for supporting the tubes independently of the shell, said frictional engagement of the tubes and the shell affording a support for the shell from the supported tubes.
4. A steam generator comprising a centrally disposed combustion chamber, a heat absorbing chamber surrounding the central combustion chamber, a partition dividing the said chambers and comprising a plurality of heat absorbing coils, other heat absorbing conduits relatively openly spaced and adapted to be traversed by the hot gases enroute from the combustion chamber to the heat absorbing chamber, and other coils disposed in the heat absorbing chamber, and means connecting the various coils to permit a liquid to flow first through the relatively openly spaced conduits thence through the partition forming coils and thence through the heat absorbing coils in the heat absorbing chamber.
5. A steam generator including a combustion chamber, a heat absorbing chamber, and a plurality of groups of tubes in the absorption chamber, and air preheating means including in combination therewith, a supporting casting, means for supporting the plurality of tubes in the chamber from said casting, said air pre-heater comprising detachable sections about the tubes, said sections also receiving vertical support from said casting.
6. A steam generator including means forming a combustion chamber, a heat absorbing chamber therearound and an air pre-heater around the heat absorbing chamber, said air pre-heater comprising in combination, a plurality of independently detachable air pre-heater boxes which are disposed around the aforesaid heat absorbing chamber.
7. A steam generator including a combustion chamber, a heat absorbing chamber therearound and an air pre-heater around the heat absorbing chamber, said air pre-heater comprising a plurality of independently detachable air pre-heater boxes, a supporting base, and supplemental means for supporting the aforesaid air pre-heater boxes from said base.
8. A steam generator including means forming a combustion chamber, heat absorb-
- ing means therearound and an air jacket completely around the generator through which the air for supporting combustion passes on its way to the combustion chamber, said air jacket comprising in combination a plurality of independently detachable air pre-heater boxes.
9. A steam generator comprising in combination with a base, a combustion chamber, of heat absorbing means therein comprising a tube section disposed at and forming the wall of the combustion chamber, a plurality of openly spaced loops connected to said tube section, said loops supporting said tube section from the aforesaid base, means for admitting cooling water first to the open loops, and means for thereafter passing the water from the open loops into the tube section.
10. A steam generator comprising in combination with a base, a combustion chamber, of heat absorbing means therein comprising a tube section disposed at and forming the wall of the combustion chamber, a plurality of openly spaced loops connected to said tube section, a heat absorbing chamber without the combustion chamber, said loops supporting said tube section from the aforesaid base and said loops by the openings therebetween also affording an entrance passage for the hot gases from the combustion chamber into the heat absorbing chamber.
